LOOSE-LEAF BINDER

Frank Stanley Schade, Holyoke, Mass., assignor
to National Blank Book Company, Holyoke,
Mass., a corporation of Massachusetts

Application April 4, 1942, Serial No. 437,611

7 Claims. (Cl. 129—8)

This invention relates to an improved loose-leaf binder. It is of the angle back type adapted to break from flat into inverted V-shaped form. This break is accomplished after the back portions are pulled apart flatwise. The purpose is to present the binding posts in good position for changing sheets. The binder of this type is useful in holding a large number of sheets. The construction of the binder is particularly important because of the size of the filler pack and the inherent difficulty in using a binder filled with a very large pack. It is common to use such a binder with a pack thickness of around three or four inches.

Prior art constructions of the type referred to are indicated in the Schade Patents 1,954,494 of 1934; 1,990,136 of 1935; 2,193,347 of 1940; and 2,209,284 of 1940.

A common feature of said prior patents is the substantial amount of metal used in the mechanism. A feature of my improved construction is the relatively small amount of metal used to give as good or better results. As an example, comparing empty binders of the same size intended for the same use, my new construction is just about one pound less in weight. This lighter weight gives an advantage to the individual user. It also gives an advantage to the manufacturer.

One general object of my invention is to save metal without sacrificing efficiency in the binder construction. In fact the efficiency in my new binder is improved. The results are accomplished not only by substituting lighter material for metal parts, but also by changing the form and arrangements of the parts under a comprehensive plan. I will point out the way this is done in the detailed disclosure.

The new construction involves considerable detail. The reason for its form and arrangement can be seen best from a full disclosure. This is given in the accompanying drawings and explanation.

In the drawings—

Fig. 1 is a top view of the binder with a small portion of one part cut away. The covers are seen opened out, but the back panel mechanism is seen in closed condition;

Fig. 2 is an end view of the Fig. 1 assembly;

Fig. 3 is a section on line 3—3 of Fig. 1. The cover portions are partly cut away and the scale enlarged;

Fig. 4 is a similar section on line 4—4 of Fig. 1;

Fig. 5 is a detail plan view of a lower portion of parts seen in Fig. 1 but in different position, name-

ly, the position of parts when the binder is open to give book reading position;

Fig. 6 is a view similar to Fig. 5 but with the back panel parts ready to move into their inverted V-shaped form and afterward give the binder the sheet changing position;

Fig. 7 is an end view of parts in Fig. 6 but moved to sheet changing position for the binder;

Fig. 8 is a detail view partly in section to supplement Fig. 7;

Figs. 9 and 10 are detail views to help the operating description; and

Fig. 11 is a detail view to indicate a slight modification of post construction.

I will first describe briefly the operation of the binder in its most general aspects. The positions of Figs. 1 to 4 correspond to the first open position when the binder is laid out on a table. With a full pack, not shown, the sheets are too tightly held in the back for turning to easy reading position. By pulling covers 1 and 2 apart, the two back panel parts 3 and 4 move into the position of Fig. 5. A stop pin 5 abutting a shoulder on part 6 limits this movement. When the back panel is thus widened, the sheets are loosened up at the back. They can be read much easier. Of course the book can be read in either position of Fig. 1 or Fig. 5. The latter is much easier. The reason for the former is to tightly pack the book contents at the back to save storage space. It is customary to hold loose-leaf, closely printed pages in these binders for up-to-date reference purposes. The binder is normally full to capacity and kept up-to-date by substituting printed pages. The maximum capacity of reference material in a minimum space for storage is the condition of desired use.

When pages or sheets are to be substituted, the strip 7, see Fig. 5, carrying stop pin 5, is moved to carry said pin away from the stop on part 6. Panel parts 3 and 4 are then moved wider apart than before by pulling covers 1 and 2 apart. The new position is indicated in Fig. 6. In this position, by a stop and a hinge construction to be described, the panel parts can break into angular form. They make the inverted V-shape of Fig. 7 when the binding posts 8 and 9 are swung open and apart for the sheet changing purpose. This position of parts in Fig. 7 is most convenient for such purpose. The rearrangement of parts for the closely packed storage purpose is the reverse of the movements back to the position of Fig. 1. From this position the covers are closed. I have now outlined the general operation of the binder

between storage, convenient reference, sheet changing, and back to storage conditions.

It will be seen by comparing the above operations with those of the prior art that, generally considered, the book operations are quite similar. I mean to recognize that the prior art structures have very desirable operations for book binder use. This is particularly so in the circumstances I referred to concerning the use of large capacity reference books of loose-leaf kind. According to my invention of new structure I retain the desirable operations of the prior art, and while continuing provision for such operations I arrange the new structure for effectively attaining additional advantages. As this is done by close attention to the arrangement of detail elements in combination, such additional advantages will be referred to further after the structural detail is described.

I will now describe the example of specific construction in my improved binder. Back panel part 3, Fig. 3, is made of stiff cardboard. It is covered by cloth or a suitable layer of decorated covering and book finishing material 10. Such layer 10 is turned over the free outer edges of part 3. On the left edge, layer 10 is extended vertically and partially covers up to gap 12, an additional part 11. The latter is a wooden bar. It lies along the margin of panel 3.

Wooden bar 11, as shown, has a specially shaped cross-section. A similar wooden bar 13 lies along the right margin of panel 4. Bar 13 has a similar cross-section to that of bar 14 except that its base has a higher level.

The cross-sectional shape of bars 11 and 13 has these advantages: Its lower or broad base portion gives firm and flat support to a substantial area along the margins of panels 3 and 4. Its upper central vertical flange portion 14 or 15 of substantial width is integral with the lower portion. The flange provides abutting support for the binding margin 17 or 18 of covers 1 or 2. Such margin is beveled along the lower edge to fit a complementary bevel extending inwardly from the outer side of the bar. Thus, a good seat is provided for binding cover margin 17 or 18 on its adjacent bar 13 or 11. The cover margins are riveted respectively to flanges 14 and 15. The arrangement also provides a convenient way to stop off and bind the edges of flexible layers 10 and 19. They are laid in the bevel angle in 11 and 13 and stopped off at gaps 12. The upper edges of these small gaps are the stop-off lines for flexible cloth strips 20 extending down from hinges 21. A second decorative flexible cloth covering 20' is attached to the outer side of covers 1 and 2 and the binding margins 17 and 18. This also serves to reinforce the cloth strip 20 at the hinge 21. The said riveted cover margins bind the strips 10, 19, and 20 very effectively on bars 11 and 13. The arrangement gives a good, neat appearance with easy assembly and low cost. The raw edges are covered and well anchored as the drawing shows. The outer surfaces of the binding margins 17 and 18 are substantially flush with the outer surfaces of bars 11 and 13. Thus, the side of the book has a simple, neat appearance. The thickness of the flanges 14 and 15 is substantial, as shown. That is, they are quite a bit thicker than if metal flanges were used. The ones indicated are of wood, for example, and need to be thicker to give strength.

Compared to metal flanges, the relatively thick wood flanges 14 and 15 do not, as a matter of 75

fact, materially interfere with the desired thickness of the filler pack or sheet capacity of the binder. It might seem otherwise, considering that these flanges carry binder posts 8 and 9 and the sheet capacity must stop where the posts stop. The flanges 14 and 15, it will be noted, have their opposed inner faces positioned well in from the inner vertical faces of bars 11 and 13. The base portions of the bar are undercut somewhat at chosen places, as will be explained. This is to accommodate telescoping movements of the mechanism for manipulating the back panel portions of the book. The result is that the sheet capacity of the binder is maintained just about equal to what it can be when thin sheet metal flanges were used. The latter have not been spaced apart in practice and the space between filled with sheets. Part of the available width between the flanges was necessary apparently to accommodate the binder operating mechanism. The latter has taken enough space to interfere with a sheet capacity otherwise available when thin metal flanges were used.

I have taken this condition into consideration 25 in making my improved structure. I use what has heretofore been lost space. It is used to make flanges 14 and 15 of lighter, cheaper material, as wood, and thick enough and shaped appropriately to give all the strength needed 30 where it is needed. Instead of making my binder thicker in overall dimensions for a capacity equal to prior art constructions, I make it approximately of the same overall size.

A feature of keeping the overall binder width 35 down is seen in my hinge construction and positioning of parts. The binding margin 17 or 18 of a cover is above the base portion of 11 and 13. The latter is wide enough in cross-section to give strength. A part of this width is used 40 by the said adjacent binding margin being mounted to abut the post holding flange. The total book thickness is kept down by the total thickness of 17 and 18, see Fig. 3. They add nothing to the overall width.

45 In my construction the cover hinges 21 are located as shown close to the upper level of the flanges 14 and 15. When the covers are closed against full binder contents, there is very little waste space. The pack, bound tightly between flanges 14 and 15, tends to fan out a bit above the posts. The covers, held in vertical position, tend to hold the pack in and restrain the pack-fanning tendency. There is only one very small empty recess along one side of the pack against each cover. It is the little recess between a hinge 21 and the inner upper edge of the adjacent flange 14 or 15. The hinge 21, being positioned close to its adjacent flange at its upper level, minimizes and makes such recess very small. It is hardly noticeable. Viewed endwise, a full and closed binder gives an improved appearance over prior art books, as I view it. And, even though strong, relatively bulky bars of wood are used in my construction, the appearance of increased book bulk is certainly avoided, while the overall bookbinder dimensions are kept approximately the same as when relatively thin sheet metal angle construction is used.

50 A part of the space-saving arrangement is indicated in Fig. 4. The bar 13 is shown undercut to make the recess or pocket 22. In the book position of Fig. 1 the rounded end portion 23 (see Fig. 5) of metal strip 24, is pocketed in the space 55 22. A similar construction is provided metal

strip 25, see Fig. 1, near the other end of the back panel mechanism.

This mechanism will now be described. Panel 4, made of cardboard or non-metallic material such as wood, for example, extending from the bar 13 rests on panel 3 and below metal strips 24 and 25 and is so held that, while it may be drawn smoothly and easily from one position to another, it is firmly supported at all times (Fig. 4). A fabric material 26 covering the panel 4 extends beyond it to encase a wire 27, thus forming a hinge at 28, as will be shown later. The fabric 26 continues under the panel 4, thus completely covering it top and bottom along its entire length. It is of sufficient stiffness to extend horizontally from the panel 4 and support the wire 27, yet is sufficiently flexible to bend when in the position shown in Fig. 8. The wire 27 has a loop 29 underlying metal strip 24. In Figs. 1 to 4 loop 29 fits into the recess 30 cut in the bar 11, while in Figs. 6, 7, and 8 it encircles the struck-down portion 31 of the metal strip 24. This struck-down portion 31 is pinned to the lower panel 3 by the rivet 32. As the panels 3 and 4 are moved relative to each other the portion 31 passes along the slot 33 (Fig. 5) formed in the panel 4 and its fabric covering 26 until the position of Fig. 6 is reached. At this point the book back may be "broken" to permit pages to be extracted or added, as illustrated in Fig. 7. In this position the loop 29 encircles that portion 31 of the metal strip 24 as has been mentioned before, and the fabric covering 26 extending beyond panel 4 bears on the end of panel 3, forming a simple yet effective hinge at 28 which may be used to bring the panels 3 and 4 to any desired angle with respect to each other, as shown in Figs. 7 and 8. Only the lower half of the book has been illustrated and explained with respect to the foregoing mechanism, but it must be understood that a similar arrangement of parts is provided and associated with metal strip 25 shown in Fig. 1.

At the upper and lower extremities of the wire 27 two additional loops 34 and 35 are disposed oppositely from the loop 29. These loops normally are inoperative, but they come into use if any attempt is made to bend the book inwardly when in the position of Fig. 6, since these loops 34 and 35 bear against panel 4 and the loop 29 in the position of Fig. 6 bears against panel 3, thus restraining the panels against bending inwardly.

Slidably attached to the metal strips 24 and 25 is the narrow, thin strip 7 briefly mentioned before. Small lugs 36, struck from the metal strip 24 and 25, are provided to hold the slidable strip 7 in line, holding it from lateral movement while permitting it to slide longitudinally, limited by the shoulders 37 and 38 bent in the strip 7 to furnish lower and upper stop positions, as seen in Fig. 1.

Carried by the strip 7, the stop pin 5 rests in the slot 39 of the plate 40 when in the position shown in Fig. 1, abuts the stop shoulder 41 in the position of Fig. 5, and rides clear of shoulder 41 to the position of Fig. 6 when the strip 7 is pushed manually to its upper position. There is a finger bend 7', seen in Fig. 2, for convenience in manipulating strip 7.

The plate 40, fixed to panel 4 in any suitable manner, as by rivets, has two cam surfaces 42 and 43. Cam surface 42 is utilized to return the stop pin 5 to its lower position when the book is being closed (Fig. 9). Cam surface 43 is used

to offset the stop pin to clear the stop shoulder 41 on closing the book if the strip 7 carrying pin 5 should accidentally be pulled to its lower position while the book is open to its full extent. 5 The operation is indicated in Fig. 10.

Fig. 11 shows a modified form of binding post structure. The binding post 9, instead of being unsupported at its free end, fits into a socket 9' in a stub post. This structure not only serves to support the post 9, but also serves to some extent as a guide for the post and so helps to keep the two telescoping halves of the book in proper alignment.

The posts 8 and 9 are preferably made of wood or nonmetallic material. They are mounted in opposite sets held respectively by the flanges of wooden bars 11 and 13.

I have disclosed my invention in the form now best known to me for practicing it to advantage. 20 Considering the character of the detailed drawings I have not thought it desirable to expand the description. It is clear that the structure and its operation as compared to the prior art binders will accomplish what I stated in the 25 beginning.

What I claim is:

1. A post binder of large capacity and of comparatively light weight comprising in combination, a back panel construction of two flat parts 30 adapted to slide one on the other, each part provided with a bar of substantial thickness resting on its outer edge margin, each bar including an intermediately located vertical flange along its upper length for carrying binder posts, a longitudinal shelf along the outer side of each bar provided by the distance between its flange connection and said outer side, a cover having a binding margin fastened against each flange and seated on its shelf, a cover hinge between the 40 cover and said binding margin, the line of said hinge being located close to the upper level of the adjacent flange, and back panel manipulating mechanism to control the relative positions of said flat parts in their movements, said bars 45 having recesses along their lower sides adapted to accommodate parts of said mechanism when the binder is in closed condition, said manipulating mechanism having a flexible hinge of material such as cloth extending beyond the outer 50 edge of one panel and provided with a beaded edge and fingers carried by the other panel to engage the beaded edge for holding it for making the hinge over the outer edge of such other panel when desired all constructed and arranged for 55 the purpose described.

2. In a construction of the kind described, two stiff slidable back panel parts, one having a flexible hinge strip with a reenforced bead extending longitudinally beyond and along its inner edge, the other one having two spaced light weight strips positioned to overlie the first one, each of said strips having means at one end to engage said reenforced bead whereby a hinge line is predetermined for said flexible strip to turn from 60 when the panel parts are separated for relative hinging movements, a stop pin, a slidable member mounted on said light weight strips to carry the pin, a cam member movable with the panel part having the hinge strip, said cam member having a part to abut said pin and cam surfaces to move said pin into line for engaging said abutment whenever the panel parts are separated for hinging movements and then returned therefrom to non-hinging position.

3. The structure of claim 2 in combination with

means to prevent bending of the panel parts in more than one direction from the flat hinging position.

4. A post binder of large capacity and of comparatively light weight comprising an expandable back portion of stiff panel parts, stiff bars with flanges to hold opposite sets of posts, all such parts being of non-metallic material, wood for example, panel manipulating mechanism associated with said panel parts, such mechanism being adapted to constrain the panel parts for movements to several predetermined positions, namely a full panel overlapping book closed position, a partially overlapping position, and a hinging or panel angle position for a sheet changing operation, a finger-operated latch device to automatically avoid the last-named position until the latch is consciously operated to permit it, parts of said mechanism being arranged to telescope in recesses of the non-metallic parts when the book is in full closed position, said panel manipulating mechanism including beaded cloth hinge strip extending beyond the outer edge of one panel and fingers to engage said bead to hold it for the cloth strip to bend over the outer edge of the other panel as a hinge line, all for the purpose described.

5. In a large capacity post binder of the kind described having a binder back construction made of two complementary panels one mounted on the other for expanding, contracting and hinging movements, relatively thick non-metallic bars one fastened along the outer margin of each panel, posts mounted on the upper margin of each bar, one of said panels having a flexible hinge strip extending a short distance beyond its inner margin, a stiff reenforced outer bead on said hinge strip, two spaced loops extending beyond said bead, slots extending across said panel one in line with each of said loops for the purpose of receiving movable fingers adapted to engage said loops, means overlying said other panel having fingers to engage said loops when the two panels are separated far enough whereby said bead and loops are held for a predetermined hinge line, said bars being provided with recesses on their

under side, such recesses of one bar being extensions of said slots to accommodate the construction of said fingers and the recesses of the other bar being in line with said loops to accommodate them when the complementary panels are contracted to close the binder back construction.

6. In a large capacity post binder of the kind described having a binder back construction made of two complementary panels one mounted to slide on the other into relative binder closed, reading, and "broken" back position for changing sheets, mechanism adjacent the panels to control their movements, such mechanism including a thin narrow latch strip always overlying one of the panels and slidably mounted lengthwise thereof between latching and unlatching position, a stop member carried by said strip, a permanently positioned stop shoulder on the other panel to engage the stop member on the latch strip, and means on the last-mentioned panel to automatically shift the latch strip in position to have the stop member engage said stop shoulder whenever the panels are moved together from positions beyond the panel latched position, said panels carrying hinge parts for relatively angular movement when separated beyond the panel latched position.

7. The sub-combination in a binder of the kind described comprising two stiff relatively slidable back panels, one having a flexible hinge band along its inner edge and extending slightly beyond such edge, a stiff rod reenforcing said hinge band in a beaded edge, means overlying the other panel below which the first panel and its hinge band are adapted to slide back and forth while such means hold the panels in parallel position, hinge means arranged to cooperate with said hinge band and provide for panel hinging movement when the panels slide to a predetermined hinging position, said rod being provided with offset portions to engage both panels and said overlying means so as to prevent the panels turning from their horizontal positions into an angular position except in one direction.

FRANK STANLEY SCHADE.
